Inventor

UNITED STATES PATENT OFFICE

GEORGE PAR CHURUS, OF NEW YORK, N. Y.

ROCKING FIGURE TOY

Application filed August 21, 1930. Serial No. 476,903.

This invention relates to toys and more particularly to a rocking figure toy.

An object of the invention is to construct a toy of the character indicated capable of being operated by a simple spring motor.

Another object of the invention is to provide a toy which simulates in its operation what is commonly known as a hobby horse.

A further object is to provide a toy of the type suggested, which will be positive in its mode of operation, simple in construction and durable in use.

Other objects will appear as the description proceeds.

15 In the accompanying drawings which constitute a part of my specification,

Figure 1 is a view in side elevation of my improved toy;

Figure 2 is a sectional view taken on the line 2—2 of Figure 1;

Figure 3 is a sectional view taken on the line 3—3 of Figure 1, and

Figure 4 is a sectional view taken on the line 4—4 of Figure 1.

25 Like characters of reference are used throughout the following specification to designate corresponding parts.

A pair of arcuate rockers R are held in spaced relationship by a plurality of metal 30 spacing members 10, 11, 12 and 13. Both of the members 12 and 13 are characterized at their ends by inturned lugs 15, 15a which extend about and embrace the outer sides and the bottom of the rockers R. Similar lugs are 35 stamped from the spacing members as indicated at 16, 16a to embrace the inner sides of the rockers, so that the rockers are rigidly maintained in spaced relationship.

40 Both of the members 12 and 13 have also stamped therefrom at their ends above the rockers eyes 17, 17a for receiving the apertured hoofs 18, 18a of pairs of legs 19, 19a of a figure horse body H. The upper ends 45 of the legs are rigidly secured to the body of the horse at 20. Seated upon and straddling the horse is a toy rider B. It will be appreciated that the figure is not necessarily limited to that of a horse as it may take the 50 form of any other animal or even of an inani-

mate object as for example, a rocking chair having a human figure seated thereon.

The horse is mounted for rocking movement upon a base 21, which has intermediate its ends and on opposite sides thereof a pair 55 of parallel arms 22, 22a. Each of these arms is characterized by an aperture 23 there-through forming seats that receive a bearing shaft 24, which shaft is spread at its terminal portions as at 25 to maintain it in fixed position upon the arms 22, 22a. The spacing member 12 has extending upwardly therefrom a pair of parallel lugs 26 which are mounted for rocking movement on the shaft 24 as clearly shown in Figure 3. Additional gripping elements 27 are stamped from the spacing member 12 and these receive the rockers R.

An upright arm 28 is mounted on the base and has secured thereto at its upper end a coil 70 spring S. The opposite terminal of the spring is fastened to a lug 29 forming part of the spacing member 13.

The motive means for operating the toy consists of a spring motor M mounted upon 75 the base 21 intermediate the arms 22 and 28. This motor is characterized by a conventional clock spring, operating a train of gears, 32, 33, 34 and 35 when the spring is wound up by means of a key 36. Rigidly secured to the 80 gear 35 is a crank shaft 37 which has pivoted thereto as at 38 an operating shaft 39. The opposite end of this shaft is pivoted to a bearing 40 secured between two downwardly extending lugs 41 stamped from the mem- 85 ber 11.

The mode of operation will now be apparent. The spring motor is wound up by means of the key 36 and the figure is held against movement by being grasped in the hand. 90 When sufficient energy has been stored in the spring the hand is removed from the figure. The throw of the crank 37 rearwardly in the direction of the arm 28 exerts a pull upon the operating shaft 39 to rock the figure forwardly about the shaft 24. This accordingly tensions the spring S which is maintained in this condition until the crank arm completes half its revolution and commences moving forwardly. The function of the 100

spring is primarily to prevent the figure from becoming unbalanced when rocked about the shaft 24.

From the above description taken in conjunction with the accompanying drawings it will be seen that I have provided a toy which can be manufactured at a small cost and which will be very entertaining to a child. Many minor changes in detail of construction may be resorted to without departure from the spirit of the invention.

Having thus described my invention, what I claim as new and desire to secure by Letters Patent of the United States is:

- 15 1. A rocking toy comprising a base, a pair of rockers pivotally supported by the base, a vertical arm secured to one end of the base, a motor operatively associated with the rockers, and a spring connected to the rockers and to the vertical arm.
- 20 2. A rocking toy comprising a base having upstanding parallel arms, a bearing shaft mounted in the arms, a pair of rockers having a figure thereon, a plurality of spacing members for the rockers to which the figure is attached, one of said members pivoted to the shaft, and means on the base for actuating the last mentioned member to rock the figure about the shaft.
- 25 3. A rocking toy comprising a base, a pair of pivotally mounted rockers supported by the base, spacing means for the rockers comprising a plurality of sheet metal members having lugs stamped therefrom to embrace
- 30 35 the rockers, a depending bearing carried by one of the members, a motor mounted on the base, a crank operated by the motor, an actuating shaft pivoted on the bearing and to the crank, and a spring having one end secured above the base and its opposite end to a spacing member.

In testimony whereof I affix my signature.
GEORGE PAR CHURUS.
